(57) **CLAIM**

The ornamental design for an egg carton with bubble cell pockets, as shown and described.

DESCRIPTION

FIG. 1 is a bottom perspective view of an egg carton with bubble cell pockets;

FIG. 2 is a front elevational view thereof;

FIG. 3 is a rear elevational view thereof;

FIG. 4 is a right side elevational view thereof, the left side elevational view being a mirror image thereof; and,
FIG. 5 is a bottom plan view thereof.

The broken lines illustrate portions of the egg carton with bubble cell pockets and form no part of the claimed design.
